COMBINED COFFEE URN AND DISPENSING CABINET

Ford Se Bastian, Merion, Pa., assignor to Coffee Chef Corporation, Merion Station, Pa., a corporation of Pennsylvania

Filed Dec. 6, 1962, Ser. No. 72,751

Term of patent 3½ years

(Cl. D2—3)

Fig. 1.

Fig. 2.

Fig. 3.

FIG. 1 is an elevational view taken from one side of a combined coffee urn and dispensing cabinet, showing my new design, the rear being substantially plain;

FIG. 2 is a front perspective view thereof taken from the side opposite that shown in FIG. 1; and

FIG. 3 is a top plan view thereof.

I claim:

The ornamental design for a combined coffee urn and dispensing cabinet, as shown and described.
